UNITED STATES PATENT OFFICE.

SIXTO OCAMPO, OF NEW YORK, N. Y.

MEANS FOR THE SYSTEMATIC CONTROL OF ELECTRIC CIRCUITS BY LIGHT-RAYS.

1,072,152.

Specification of Letters Patent.

Patented Sept. 2, 1913.

Application filed March 14, 1913. Serial No. 754,178.

To all whom it may concern:

Be it known that I, Sixto Ocampo, a subject of the Kingdom of Spain, residing at New York city, in the county and State of New York, have invented certain new and useful Improvements in Means for the Systematic Control of Electric Circuits by Light-Rays, of which the following is a clear, full, and exact description.

10 The object of this invention is to control electric circuits, particularly circuits leading to electric lamps to cause various configurations or designs to appear upon a bank of lamps, such as are used for advertising purposes, for theater cab calls and the like, so that any combination of lights desired may be caused to appear upon the bank in luminous contrast to the rest of the lamps by means of stencils or light obscuring films, which may be passed by an operator between a light emitting source and a control board of selenium units. This source of light may be an ordinary lamp and lens, in front of which various cut stencils or films 20 may be inserted to cut off the light to certain units of selenium. The control board consists of a great multitude of separate selenium piles, each pile controlling a circuit making switch, each switch controlling at 25 least one lamp on the lamp board.

The selenium piles have the property of becoming good conductors of electricity when under the influence of light thrown upon them, and poor conductors when the 30 light is obscured. Consequently if light is thrown upon the entire area of the control board, so as to render all the units of selenium fairly good conductors, all the switch magnets will be operated, and all the 35 lamp circuits closed, causing the entire board to be illuminated, but if the ray of light is obscured from any given unit or series of units, the resistance of those units will be increased to such an extent that the pull on 40 the armature will not be great enough to overcome a tension spring, and hence the circuit to those lamps which are in connection with the particular magnet switch of the obscured unit or series of units will not 45 be lighted so that an operator at the source of light by placing any type of stencil which will obscure rays of light which are thrown on the selenium piles can control by the 50 shape of light obscuring stencil the resistance of the units, and hence the number of 55 lights and the position of lights will be

illuminated upon the board. Thus if a plain stencil having the letter A cut out is placed before the projecting lens, the light will fall on the units to form an "A" thereon, and the lights on the lamp board will immediately reproduce this letter A. Of course any number of lamp boards may be controlled by a single selenium pile transmitter.

60 In place of a cut-out stencil such as described as the simplest form of invention it will be possible to project on the selenium pile transmitter rays of light from an ordinary projecting machine, and moving picture film, so that the light as it is obscured by the dark portions of the film will create its impression upon certain selenium piles to cause them to operate or not according to the degree of obscuration of the light. 70 While I have shown a lamp board having only one color of lamp, and a selenium pile having one unit section for each individual lamp, and a single film so that block or outline in black and white contrast can be produced on the board, nevertheless I do not wish to limit my invention to such simple form of device, for it will be obvious that the color of the lights may be changed, and different piles caused to control different 80 colors and separate films or stencils used for selecting color, or a combination of colors desired to be reproduced.

85 In the accompanying drawings, I have in a general diagrammatic way illustrated 90 the accompanying invention sufficiently so that one skilled in the art and possessed of the knowledge of the phenomena attending the use of the selenium will be able to practise the invention.

95 The scope of my invention will be pointed out in the claims.

In the accompanying drawings: Figure 1 is an illustrative view of a selenium transmitter switch, and lamp board. It will be 100 understood that I have shown but a few of these units when in reality there would be many thousands of them. Fig. 2 shows an enlarged face view of a single selenium pile drawn to a greatly enlarged scale. Fig. 105 3 is a section in line 3—3 Fig. 2. Fig. 4 is a diagram showing five selenium cells or piles in circuit with the electric switches and the lamps. Fig. 5 is a diagrammatic view of a projecting machine and film, and 110 a side elevation of the selenium transmitter.

In the accompanying drawings, 1 repre-

sents a projecting machine; 2 the projecting film or stencil; 3 the selenium transmitter which is divided up into many hundreds or thousands of square selenium cells or 5 piles. There are shown only fifty-six in the drawing, but it is understood that this is merely diagrammatic.

4, is the lamp board having a multitude of lamps, such as incandescent electric lamps 10 5 thereon, at least one for each selenium cell. Each cell 6 is formed of the overlapping plates 7 and 8, alternate plates being connected to conductor boards 9 and 10, and between the boards and the plates the 15 selenium 11 is interposed in the ordinary manner known to the art. The conductor rods 9 and 10 are connected by wires 11^a and 12, with a source of current 13, and a magnet 14 adjacent to an armature 15, which 20 is normally held away from the magnet by a spring 16, and tension screw 17, so that a predetermined amount of current must pass through the magnet 14 before the armature is attracted to permit its contact 25 locks 18 contacting with contact points 19 and 20, each connected with a wire 21 and 22. The wire 22 leads to a lamp 5 from which a wire 23 leads to a source of lighting supply, while the wire 21 leads to the other 30 source of electric light current supply.

As explained in the fore part of this specification, the adjusting screw 17 will be so regulated that the spring 16 will normally prevent the operation of the armature, 35 which will be prevented until light is thrown upon the selenium unit, which light will reduce its resistance, and cause sufficient current to flow through the magnet 14 to overcome the spring and make the contact to 40 supply current to that lamp which is controlled by the particular selenium unit.

In carrying out this invention, details of construction may be varied from those shown, and yet the essence of the invention be retained; some parts might be employed without others, and new features thereof might 45 be combined with elements old in the art in diverse ways, although the herein described

type is regarded as embodying substantial improvements over such modifications. 50

As many changes could be made in the above construction, and many apparently widely different embodiments of the invention could be made without departing from the scope thereof, it is intended that all 55 matter contained in the above description or shown in the accompanying drawings shall be interpreted in an illustrative and not in a limiting sense.

It is furthermore desired to be understood 60 that the language used in the following claims is intended to cover all the generic and specific features of the invention herein described, and all statements of the scope of the invention which as a matter of language 65 might be said to fall therebetween.

I claim as my invention:

1. The herein described apparatus for reproducing figures from a stencil equivalent, consisting of a source of light, the stencil 70 equivalent, the board containing a multitude of units, the resistance of which is effected by the throwing of light thereon, electrical connections from said units, and a board having a multitude of lights thereon, at 75 least one light for each unit.

2. The herein described apparatus for reproducing figures from a stencil equivalent, consisting of a source of light, the stencil equivalent, the board containing a multitude 80 of units, the resistance of which is effected by the throwing of light thereon, electrical connections from said units, and a board having a multitude of lights thereon, at least one light for each unit, a separate circuit 85 for the lights of the board, and a magnetically controlled switch controlling said circuit, and a circuit for said switch controlled by said unit.

Signed at New York city, New York, this 90 13th day of March, one thousand nine hundred and thirteen.

SIXTO OCAMPO.
